Inventor

Walter B. Marble

By his Attorney

Attorney
E. W. Marshall

UNITED STATES PATENT OFFICE.

WALTER B. MARBLE, OF CHICAGO, ILLINOIS.

VANITY CASE.

Application filed June 7, 1923. Serial No. 643,848.

To all whom it may concern:

Be it known that I, WALTER B. MARBLE, a citizen of the United States, and a resident of Chicago, county of Cook, and State 5 of Illinois, have invented certain new and useful Improvements in Vanity Cases, of which the following is a specification.

This invention relates to vanity cases.

One of the objects of the invention is to

10 provide a compact article of the character described and a device so constructed and arranged that toilet accessories such, for instance, as rouge and powder compacts contained therein will be readily accessible.

15 Another object of the invention is to provide a vanity case with a detachable container whereby the container can be removed and refilled or replaced by a filled container.

20 Another object of the invention is to provide an article of the character described that is simple in construction, comprises few parts, is attractive in appearance and can be economically manufactured.

25 Further objects of the invention will appear from the following specification taken in connection with the drawings, which form a part of this application, and in which—

30 Fig. 1 is a plan view of a portion of the vanity case, the cover of the case being open.

Fig. 2 is an elevational view of the case with the covers in open position and the 35 container also swung to a position intermediate the covers.

Fig. 3 is a sectional elevation on an enlarged scale and partly broken away showing the detachable swivel mounting for 40 the container, the container being shown in its lowered position in the lower casing member.

Fig. 4 is a sectional elevation broken away 45 similar to Fig. 3, but showing the container in elevated position, in which position it may be removed from its pivot pin, and

Fig. 5 is a sectional elevation of the container showing the slot therein for receiving the pivot pin.

50 The invention briefly described comprises a vanity case consisting of a base member and cover member and a container mounted intermediate the base and cover and having means for securing thereto a plurality of 55 toilet accessories such as compacts. The

cover member has secured thereto a mirror and the container or intermediate member is detachably swiveled on a pivot pin and preferably has secured thereto a pair of compacts such as a rouge compact and a 60 powder compact arranged back to back or facing outwardly. Either of these compacts may be used by turning the intermediate member on its swivel and when desired the container can be detached from its pivot pin for the purpose of renewing the compacts or a filled container can be inserted in the place of the used container. Further details of the invention will appear from the following description.

70 The vanity case illustrated comprises a base member 10 and cover member 11 hinged together by complementary hinge members 12 and 13 connected by a pivot pin 14. The cover member 11 has mounted 75 therein a mirror 15.

75 A container 16 is mounted intermediate the members and carries a pair of compacts such as a powder compact 17 and rouge compact 18. In assembling these parts, the 80 rouge compact is placed first in the container and extends through the central opening 19 thereof and the powder compact is placed back to back with the rouge compact and faces in an opposite direction. One 85 face of the container has formed thereon an outwardly extending lug 20 to facilitate lifting the container.

85 The container 16 is detachably mounted in the casing on a pivot pin 21 which is 90 pivoted on the pin 14. The pin 21 has a head 22 formed thereon and the container has a slot 23 with an enlarged portion 24 at one end for receiving the head 22 of the pin 21. When a container is to be mounted 95 in the casing, the head 22 of the pin 21 is inserted through the enlarged portion 24 of the container and the container is then moved to a position in which the pin 21 is disposed in the slot 23.

100 If desired, means may be provided for holding the pin 21 in the position shown in Fig. 4 and in the particular form of the invention illustrated this means comprises a spring strip 25 secured to the casing 10 and adapted to engage a notch 26 formed in the pivot ring 27 of the pin 21.

105 Any desired means may be provided for retaining the powder compact 17 in the container and in the form of the invention il-

lustrated this means comprises a split ring 30 adapted to seat in an annular groove 31 formed in the container wall.

A shoulder 32 may be formed on the inner wall of the casing member 10 and is adapted to engage an annular shoulder 33 formed on the container for supporting the container in the base member 10.

In using the vanity case hereinbefore described the cover member 11 is swung to open position and either the powder compact or rouge compact may be used by swinging the container on its swivel pin 21. When the user desires to remove the container in order to remove the compact or substitute a filled container, the container is first raised to the position shown in Fig. 4 and is thereafter rotated until the pin 21 is disposed in the enlarged portion 24 of the slot 23. The container can then be removed from the pin and the head 22 will pass through the portion 24 of the slot 23.

Although one specific embodiment of the invention has been particularly shown and described, it will be understood that the invention is capable of modification and that

changes in the construction and in the arrangement of the various cooperating parts may be made without departing from the spirit or scope of the invention, as expressed in the following claims.

What I claim is:

1. A vanity case comprising a casing consisting of a base member and a cover member, and a member detachably connected to and swiveled intermediate said base and cover and having toilet accessories secured to its opposite faces.

2. A vanity case comprising a casing consisting of a base member and cover member, and a member swiveled and detachably mounted intermediate said members and having toilet accessories secured to its opposite faces.

3. A vanity case comprising a casing consisting of a base member and cover member, a swivel pin and a container detachably carried by said pin and disposed within said members.

In witness whereof, I have hereunto set my hand this 4th day of June, 1923.

WALTER B. MARBLE.
